UNITED STATES PATENT OFFICE.

PAUL GSCHWEND, OF CANTON, OHIO.

DESIGN FOR A BRIDLE-BIT.

SPECIFICATION forming part of Design No. 20,210, dated October 21, 1890.

Application filed April 17, 1890. Serial No. 348,414. Term of patent 14 years.

To all whom it may concern:

Be it known that I, PAUL GSCHWEND, a citizen of the United States, and a resident of Canton, county of Stark, State of Ohio, have 5 invented and provided a new and original Design for Bridle-Bits, of which the following is a full, clear, and exact description, reference being had to the accompanying drawing, making part of this specification.

10 This invention relates to a new design for bridle-bits.

The leading feature of this design is shown upon the ends of the mouth-piece, and consists of the said ends provided with a series

15 of facets which are generally in the form of truncated four-sided pyramids *a*.

Having thus described my invention, what I claim, and desire to secure by Letters Patent, is—

20 The design for bridle-bits herein shown and described.

In testimony whereof I have hereunto set my hand this 15th day of April, A. D. 1890.

PAUL GSCHWEND.
